BOTTLE FIZZING ATTACHMENT

Walter J. Simmons, Milwaukee, Wis.

Application April 21, 1937, Serial No. 138,123

7 Claims. (Cl. 215—78)

My invention relates to improvements in fizzing attachments for bottles containing effervescent liquids.

Heretofore attempts have been made to provide bottles with fizzing attachments to be substituted by the user for an ordinary bottle cap or cork, but such attachments require a preliminary removal or partial destruction of the cap or cork used by the manufacturer of the beverage, and such attachments have not yet been found satisfactory in practice.

The primary object of my invention is to provide a tubular attachment which can be applied at the time the bottle is filled by the manufacturer of effervescent liquids, and which may serve as an extension of the bottle mouth piece to which a bottle capper may be applied to cap the attachment instead of capping the bottle. Thereupon the attachment can remain associated with the bottle, to be cleansed with the bottle when the bottle is returned to the factory and again used after refilling the bottle.

Further objects are to provide improved means for securing the cap to the bottle, and an improved valve mechanism peculiarly adapted to release the contents of the bottle through a fizzing nozzle.

In the drawing:

Figure 1 is a sectional view of a bottle mouth piece having an associated cap embodying my invention.

Figure 2 is a sectional view drawn to line 2—2 of Figure 1.

Figure 3 is a perspective view showing a modified bottle mouth piece and its associated cap, with the cap detached.

Figure 4 is a transverse sectional view of the lower portion of the cap shown in Figure 3 as it appears when applied to an associated bottle and secured against rotation thereof.

Figure 5 is a side elevation, partly in section, showing a modified cap applied to the mouth piece of a bottle of standard form, the cap being like that shown in Figure 1 with the exception of the means for securing it to the bottle.

Figure 6 is a view similar to Figure 1 showing a further modified embodiment of the invention.

Like parts are identified by the same reference characters throughout the several views.

The attachment shown in Figures 1 and 2 comprises a body 10 having a central vertically extending passage 11, which is preferably of the same diameter as the opening 12 in the mouth piece of the bottle to which the attachment is applied. The upper end of the passage 11 is

closed by any suitable cover, such, for example, as the disk 13 and an associated metal cap piece 14 having a skirting 15 to be pressed into interlocking engagement with an annular enlargement 16 of the upper end of the body.

The disk 13 and associated metal cap piece 14 may be conveniently termed the cap top members, since these members, in association with the body 10, constitute a substitute bottle cap.

From the passage 11, a duct 20 leads radially to an arcuate or laterally extending duct 21 (Figure 2) which leads to another radial duct 22 and through the outer wall of the body 10. The radial duct 22 is preferably provided with a nozzle insert 23.

The inner end of the duct 20 is conically enlarged to provide a seating for a valve 25, the conical face of which preferably has a rubber surfacing 26, as shown in Figure 1. The valve 25 has a stem 28 which crosses the arcuate duct 21 and extends through the outer wall of the body to receive an operating knob 30. The body is socketed to receive a spring 31 which is coiled about the stem 28, with its outer end bearing against the knob 30 to urge the valve 25 to its seat.

The knob 30 will preferably be provided with a stud-like projection 33 normally bearing upon the exterior surface of the body to prevent the knob from being accidentally pushed inwardly to unseat the valve. But when it is desired to manually unseat the valve the knob may be rotated to bring this projection 33 into registry with a recess 34 in the body, this recess being of sufficient depth to allow the knob to move inwardly far enough to unseat the valve. In the meantime the bottle may be wholly or partially inverted to allow the liquid to be expelled by pressure of the contained gas or gases.

Various means may be employed to secure the attachment to the bottle. In Figure 1 I have illustrated a bottle mouth piece having an annular enlargement, bead or rib 35. The cap body is provided with a skirting 36 having a lower marginal portion 37 adapted to be pressed into engagement with the rib 35, as shown in Figure 1. This skirting is composed of material which is sufficiently malleable or inelastic to be pressed into place and to remain permanently in place thereafter unless expanded by a suitable tube or by applying sufficient force to expand it while drawing the cap away from the bottle. The rounded contour of the rib 35 facilitates such expansion. The body 10 is subjected to downward pressure on gasket 38 while the skirting is being

pressed to the bottle mouth piece, the latter being ordinarily provided with an annular top rib 39.

In Figures 3 and 4 I have illustrated a modification in which the bottle neck or mouth piece 40 is provided with projecting anchors 41, and a skirting 36a for an attachment body 10a is provided with arcuately tapered inwardly projecting locking cams 42. These locking cams 42 are of such length that they may pass downwardly between the anchoring projections 41, whereupon rotation of the body 10a will carry the cams underneath the projections 41 with a wedging action, which effectively draws the body downwardly upon a gasket 38a applied to the bottle mouth piece.

To prevent an accidental release of the attachment by rotation I provide the skirting with set screws 45 which engage the neck or mouth piece of the bottle between the anchors 41, and preferably also engage the sides of the anchors, as clearly shown in Figure 4.

With the construction shown in Figures 3 and 4, the fizzing attachment can be readily detached from the bottle by first withdrawing the screws 45 and then partially rotating the cap to bring the cam projections 42 into registry with the spaces between the anchors 41. With this construction the fizzing caps may be removed, separately cleansed, and replaced, after also cleansing the bottle.

Referring to Figure 5, it will be observed that the body 10b has a thick skirting member 46 having a beveled lower end through which set screws 47 may extend to engage the mouth piece rib 39b for the purpose of drawing the body of the cap downwardly upon the gasket 38b. If desired, the skirting 46 may have a series of resilient lips 49 adapted to embrace the bottle neck rib 35, the lower end of each lip being inwardly curved to a slight extent to embrace the rib when the attachment is forced downwardly to seating position. Similarly, when the attachment is subjected to withdrawing tension these lips yield resiliently and allow withdrawal of the attachment.

It will be understood that the cap top members 13 and 14 may be identical with those employed for capping ordinary bottles, and may be applied and secured in place by a capping machine similar to those employed for capping ordinary bottles.

Only when the bottles are returned to the bottling factory to be refilled will it be necessary to remove the crown caps 14 from the top thereof, after which the bottles and attached fizzing caps may be cleaned in the usual manner, refilled, and recapped with conventional crown caps. This practice assures the retention in the contents of the bottle of the entire amount of gas incorporated in the beverage during bottling. If it were necessary to uncap the bottle in order to install the fizzing attachment thereon some of the gas, and consequently some of the pressure, would be lost.

One of the purposes of the invention is to make the fizzing attachment sufficiently inexpensive so that it may be permanently affixed to each bottle. One of the least expensive constructions is that shown in Figure 6, the body of which is made entirely of stampings. There is an inner sleeve at 50 integrally formed to provide a radial flange 51 seating on the gasket 38c against the mouth of the bottle. The bottle bead is engaged by an integral skirt 52 depending from the periphery of flange 51.

This inner sleeve 50 is engaged in an outer sleeve 55. The pressure used in uniting the two sleeves is sufficient to form a bead 56 for the retention of the conventional crown cap. At the same time the upper margin of sleeve 50 is thickened to a wedge shape at 57 which provides a perfect seal at this point.

Integral with the outer sleeve 55 is an extension at 58 of larger diameter which embraces the skirt 52 and is also engaged about the ring 35 of the bottle, about which it may be spun to permanently affix it to the bottle as above described. The intermediate portion of the outer stamping is pressed outwardly at 60 to provide a passage 61 extending arcuately and leading from the cavity at the outlet side of the valve 63 to the discharge nozzle 64. The valve stem 65 is flattened at 66 to receive guidance from the valve port in the inner sleeve 50 of the appliance. The outer end of the stem extends through an aperture in the outer sleeve 58 and carries a handle, preferably a cup-shaped button 67 which partially encloses the compression spring 68 which seats the valve. This handle or button 67 may be rotated to the position shown in Figure 6 to clear the fitting and permit manipulation of the valve against the compression of the spring as explained with reference to Figure 2. It will, however, be obvious that if the button or handle 67 is rotated from the position shown in Figure 6, it will engage the side of the fitting and cannot be pressed inwardly to open the valve.

During the assembly of the two stampings 50 and 55 above described, pressure is applied to assure a seal between the skirt portion 52 of the inner stamping and the larger diametered sleeve portion 58 of the outer stamping.

This device can be made very simply, and by spinning the lower margin of sleeve 58 about the shoulder 35 of the bottle the fizzing appliance 40 can be permanently attached to the bottle in the same manner as that shown in Figure 1.

It will be understood that from a generic standpoint it is immaterial to the present invention whether the skirt portions 36, 49, and 58 of the various embodiments of my invention are engaged with the ribs 35 below the mouth of the bottle or whether they are simply engaged about the bead 39 at the mouth.

I claim:

1. The combination with a bottle having a beaded mouth for the retention of a crown cap, of a dispensing appliance seated against said mouth and provided with means permanently connecting one of its ends to said bottle, said appliance comprising a tubular body aligned with the mouth of the bottle and provided remote from the bottle with a mouth and bead like that of the bottle and adapted to receive a crown cap, and means intermediate the ends of the body of said appliance for the controlled discharge of the bottle contents, said means comprising a discharge nozzle, a port circumferentially remote from the nozzle, a valve controlling said port and opening inwardly, a stem extending outwardly from the valve and provided with an exposed manually operable handle, and a spring acting on said handle in a direction to seat the valve, the body of the appliance having an internal circumferential passage connecting said port with said nozzle.

2. A dispensing appliance for bottles comprising inner and outer annular stampings in sealed connection at axially spaced points and formed to provide a circumferential passage between them,

the inner stamping having a valved port and the outer stamping having a discharge nozzle, and valve means mounted on the appliance for the manual control of discharge through said port to said nozzle.

3. A dispensing appliance for bottles comprising inner and outer annular stampings in sealed connection at axially spaced points and providing between said points a circumferential passage between said stampings, one of said stampings being adapted to seat on the mouth of the bottle and at least one of said stampings having a top providing a like mouth and cap retaining means, a nozzle mounted on the outer stamping and communicating with said passage, the inner stamping having a port communicating with said passage, inwardly opening valve means controlling said port, a stem extending through the port and through the outer stamping and provided with a manually engageable operating handle, spring means urging said valve outwardly to its seat, and means for the connection of the appliance to the bottle.

4. A dispensing appliance for bottles comprising an annular body internally shouldered for engagement with the mouth of a bottle and externally provided with a cap retaining bead, said body comprising inner and outer annular elements in sealed connection at axially spaced points and providing therebetween a circumferential passage, means for retaining said body on a bottle, of which the mouth is engaged by said shoulder, and manually operable valve means for controlling discharge through said passage, the inner element of said body having a valve port communicating with said passage and the outer element of said body having a discharge port communicating with said passage.

5. A fizzing attachment for bottle mouth pieces provided with beads to which such attachments may be anchored, comprising the combination with a tubular attachment body having an unob-

structed passage therethrough substantially corresponding in diameter with the diameter of the bottle mouth pieces for which the attachment is intended and having the upper end corresponding in contour and diameter with the cap receiving portions of such bottle mouth pieces, said passage being adapted for axial alignment with a bottle mouth piece passage, a flexible bottle engaging member at the lower end of the attachment, said attachment being also provided with a fizzing nozzle intermediate of its ends, and a manually operable valve controlling delivery through said nozzle at a point circumferentially distant from the nozzle outlet, the body having a shoulder concentric with its axial passage and formed to extend over the top bottle bead with a gasket interposed.

6. A dispensing appliance for bottles comprising inner and outer annular stampings in sealed connection at axially spaced points and formed to provide a circumferential passage between them, the inner stamping having a port opening into said passage and the outer stamping having a discharge nozzle opening from said passage and circumferentially spaced from said port, and valve means mounted on the appliance for the manual control of discharge through said port, passage and nozzle.

7. A dispensing appliance for use with bottles, said appliance comprising an inner sleeve shouldered to abut the top of a bottle, an outer sleeve in intimately pressed engagement with the upper end of the inner sleeve and extending beyond said shoulder to provide a deformable bottle clasping portion, means providing a seal between the sleeves adjacent the shoulder, and dispensing means including a valve disposed intermediate the length of the inner sleeve, the upper end of the outer sleeve being formed to provide a bead over which a crown cap is applicable.
